United States Patent Office

Des. 190,559

Patented June 13, 1961

190,559

HAND BRUSH OR THE LIKE

Joseph Vallis, 448 Spadina Road, Toronto,
Ontario, Canada

Filed Aug. 29, 1960, Ser. No. 61,914

Term of patent 14 years

(Cl. D9—2)

Fig. 1.

Fig. 2.

Fig. 3.

FIG. 1 is a side elevational view of a hand brush or the like showing my new design;

FIG. 2 is an end elevational view thereof; and

FIG. 3 is a top plan view thereof.

The side and end not shown are substantially like the side and end shown.

The dominant features of my design reside in the portions shown in full lines.

I claim:

The ornamental design for a hand brush or the like, as shown and described.
